COMBINATION SHOE HORN AND CASE

Filed Feb. 20, 1932

UNITED STATES PATENT OFFICE

ROBERT P. ELLIS STARR, OF CONCORDIA, KANSAS

COMBINATION SHOE HORN AND CASE

Application filed February 20, 1932. Serial No. 594,303.

This invention relates to a combined shoe horn and carrying case.

An object of this invention is to provide a novel combination in the form of a shoe horn and carrying case wherein the shoe horn can be conveniently carried with any type of case such as a bill fold, check book holder or the like.

Another object of this invention is to provide a case of this kind wherein the shoe horn may be used without opening of the case, the case acting as a handle for manipulation of the shoe horn during the use thereof.

The above and various other objects and advantages of this invention will in part be described in and in part be understood from the following detailed description of the present preferred embodiment, the same being illustrated in the accompanying drawing, wherein:—

Figure 1 is a detail top plan view of a device constructed according to the preferred embodiment of this invention, and showing in dotted line the device in closed position;

Figure 2 is an enlarged fragmentary sectional view taken on the line 2—2 of Figure 1.

Referring to the drawing wherein like numerals of reference designate corresponding parts throughout the several views, the letter C designates generally a case in the form of a leather or flexible case which is adapted to receive articles of various types, the case including a body 10 and a flap or closure 11. The case C is provided with one member 12 of a snap fastener and the flap 11 has a complementary fastening member 13 adapted to engage the fastening member 12 so as to hold the flap 11 in closed position on the open end of the case C.

The flap 11 comprises a flexible outer covering 14, a lining 15 and a stiffening member 16 which is interposed between the lining 15 and the outer covering 14. This stiffening element 16 may be constructed of cardboard or other material of a relatively stiff construction which has a degree of flexibility, and preferably the inner end portion of the stiffening member 16 is reduced so that the outer portion of the flap 11 outwardly of the fastener 13 may be bent or flexed without un-

fastening the fastener 13 from the element 12.

The outer end of the flap 11 is provided with a reduced extension 17, and the inner end of a shoe horn 18 is secured as by lacing 19 to this reduced extension 17 of the flap 11. By securing the shoe horn 18 to the flap 11 by the lacing 19, the horn 18 may be constructed of any desired material such as metal, composition material or the like, which is preferably of non-flexible construction and is curved transversely as is conventional with shoe horns.

The body 10 is provided with a pocket 20 to receive the shoe horn 18 when in inoperative position, this pocket being formed by sewing or otherwise securing an outer wall 21 to the covering of the body 10 with one end of the wall 21 left open to receive the shoe horn 18.

In the use of this device, the flap 11 may be left in closed position with the snap fasteners 12 and 13 engaged one with another, and the shoe horn 18 may be withdrawn from the pocket 20 by flexing the flap 11 at a point closely adjacent the snap fastener 13. When the shoe horn 18 is removed from the pocket 20, the horn may be used with the case serving as a flexible handle and as the snap fasteners 12 and 13 may be left engaged with each other, none of the articles positioned in the case C will drop out.

It is, of course, understood that various changes and modifications may be made in the details of construction and design of the above specifically described embodiment of this invention without departing from the spirit thereof, such changes and modifications being restricted only by the scope of the following claims.

What is claimed is:—

1. The combination of a case including a flexible closure flap, a shoe horn member carried by the flap and a pocket carried by the case to receive the shoe horn.

2. The combination of a case including a flexible closure flap, and means for holding the flap in closed position, a shoe horn, means for securing the horn to the flap and a pocket carried by the case to receive the shoe horn.

3. The combination of a case including a flexible flap, fastening means carried by the flap and the case to secure the flap to the case, a shoe horn, a reduced extension formed with the flap, means for securing the horn to the flap, and a pocket carried by the case to receive the horn and hold the horn in inoperative position.

In testimony whereof I hereunto affix my
10 signature.

ROBERT P. ELLIS STARR.
